FUSE PLUG

Henry Ruskin, Chicago, Ill.

Application January 12, 1934, Serial No. 706,317

9 Claims. (Cl. 200—125)

My invention relates to fuse plugs, particularly to multiple fuse plugs in which a number of fuse links are provided and arranged for selective inclusion in a circuit to be protected, so that by the turning of a switch element forming part of the plug structure an intact fuse link may be substituted in the circuit for a fuse link which has been blown.

An important object of the invention is to provide an arrangement in which each fuse linkage for connecting the plug terminals comprises a main fuse element and a comparatively lighter or pilot fuse element, with the fuse elements connected in a parallel or shunt relationship and with the fusion or explosion point of the main fuse element confined within an explosion chamber and the fusion or explosion point of the lighter or pilot fuse element at some other location to be visible from the exterior of the plug so that the blown fuse linkages may be distinguished from the intact fuse linkages.

A further important object is to provide an individual explosion chamber for the main fuse element of each fuse linkage and a corresponding individual visibility point for the pilot fuse element.

Another important object is to provide improved arrangement for assuring adequate and good electrical contact between the fuse linkage terminals and the plug terminals.

Still another object is to provide simple and substantial parts for the plug structure which may be readily assembled in cooperating relationship for the consecutive or selective inclusion of any of the fuse linkages in the circuit to be protected.

The above enumerated and other features of the invention are incorporated in the structure disclosed on the drawings, in which drawings—

40 Figure 1 is a top view of my improved plug;

Figure 2 is a section on plane II—II of Figure 1;

Figure 3 is a top view of the plug with the upper or rotatable element removed;

45 Figure 4 is a lower end view of the plug body with the fuse linkages therein;

Figure 5 is a plan view of the plug bottom member;

Figure 6 is a side elevation of one of the fuse 50 linkages;

Figure 7 is a top view of one of the fuse linkages; and

Figure 8 is a perspective view showing a modified fuse arrangement.

55 The plug shown comprises the body element

A, the top or cover element B, and the bottom element C. The body part A comprises a cylindrical annular wall 10 from whose upper part extends a flange structure comprising the horizontal portion 11 and the vertical or annular portion 12 which extends a distance above the upper edge of the wall 10, the top of the horizontal flange part 11 being a distance below the upper edge of the wall 10.

Substantially midway between its ends the wall 10 has the cross wall or partition 13 and the walls 10, 11, 12 and 13 all form part of an integral preferably molded structure of suitable insulating material.

Depending from the partition wall 13 is the lug 15 14 between which and the wall 10 extend radial partition walls 15 which divide the space below the wall 13 into explosion chambers 16, six such chambers being shown. The partition 13 and the upper end of the wall 10 define a cylindrical 20 terminal or contact chamber 17.

The top or cover structure B comprises a cylindrical body 18 fitting into the flange part 12 to form a top closure for the contact chamber 17, the depending flange 19 of the cover body 18 extending down between the flange part 12 and the wall 10 and seating against the top of the flange part 11. An enlargement or boss 20 extends radially on the cover body 18 from the central part thereof and overhangs and engages the top of the 30 flange part 12, this boss serving as a handle or finger grip whereby the cover structure B may be rotated on the body part A.

The bottom member C comprises the tapering body 21 extended at the top to form a flange 22, 35 the flange abutting the lower end of the wall 10 so that the bottom part C forms a bottom closure for the explosion chambers 16. The member C has the cylindrical boss 23 on its top for engaging in the recess 24 in the lug 14, such engagement 40 centering the part C on the part A of the plug structure.

Extending axially through the bottom part C and through the wall 13 and its lug 14 is a cylindrical pin or rivet 25 which continues through 45 the contact chamber 17 and through the opening 26 in the cover body 18 and into the enlarged opening 27 in the boss 20. At its lower end the pin has the flange or head 28 abutting the bottom of the part C and at its upper end the pin is tubular and is deflected to form a flange 29 for abutting against the top of the cover body 18 so that the parts A, B and C are held together 50 against axial displacement but permitting rotary 55

movement of the cover part B relative to the body part A.

The cover or top part B has the cylindrical depending projection 30 fitting and engaging in 5 the terminal or contact chamber 17 and has a radially extending slot or pocket 32 for receiving the contact member S. The member shown is formed of a length of resilient metal band bent to S-shape with the inner end 33 bent to circular 10 form to receive and intimately clamp the pin 25, the outer end 34 of the spring extending tangentially for extended contact engagement with fuse elements. As the top or cover part B is rotated, 15 the spring within the radial pocket 32 will follow such rotational movement for engagement of the spring end with the desired fuse structure. The partition wall 13 may have the annular bead 35 at its upper side surrounding the pin 25 to afford a bearing surface for the contact spring as 20 it follows the movement of the cover part B.

The pin and contact spring form the movable terminal of the plug, the other terminal for the plug being the shell 36 having the threading 37. The shell has the opening 38 in its base for receiving the lower part of the plug bottom member C and for abutting against the flange 22, the cylindrical body of the shell surrounding the lower end of the wall A.

As shown in Figures 1 to 4, each fuse structure 30 F is a band of fuse material cut out to leave two fusion restrictions or necks 39 and 40, the neck 39 being wider and of greater cross-section and forming the main fusion point while the neck 40 is of much less cross-section and forming the 35 pilot fusion point. Each fuse structure extends longitudinally around the wall 10 and through one of the explosion chambers 16 with the main fusion point 39 within the explosion chamber and the pilot fusion point 40 extending across the top of the wall 10. There is sufficient clearance space between the body 18 of the top member B and the top of the wall 10 for the passage of the fuse bands and the part of the wall 10 surrounding the contact 40 chamber 17 has channels 41 in its inner side for receiving the fuse bands, these channels communicating with passages 42 through the partition wall 13. In the lower edge of the wall 10 are the transverse channels or grooves 43 through 50 which the fuse bands extend and the lower plug member C has lugs or projections 44 on its upper side engaging in the channels 43 to hold and align the fuse structures and also to lock the part C against rotation relative to the part A. The flange part 11 on the wall A has the passageways 45 therethrough for the fuse bands, the flange 19 on the body 18 of the top part B being of sufficient greater diameter than the wall 10 to permit passage of the fuse bands. The fuse bands are applied to the body part A before application thereof to the top and bottom parts B and C. The 55 passages 42 are flared at their lower ends so that the fuse bands may be readily inserted upwardly through the passages and into the channels 41. The upper ends of the fuse bands are then deflected across the top of the wall A with the pilot fuse sections 40 extending thereacross, the fuse band ends then being deflected downwardly through the passages 45 and with their ends extending into the circumferential groove 46 in the 60 wall A below the flange part 11.

The heavier fuse points 39 of the fuse bands will be located in the respective explosion chambers 16 and the lower ends of the bands are deflected outwardly through the channels 43 and

then upwardly along the outside of the wall 10 and with the ends extended into the groove 46 overlapping the other ends of the bands.

After the fuse structures have thus been properly placed the top and bottom parts B and C are applied, the contact spring having first been slipped over the pin 25, and the pin is then riveted over at its upper end so that the plug structure parts are locked together. The terminal shell 36 is then applied and its upper edge is deflected into the groove 46 and against the ends of the fuse bands to make electrical contact therewith.

When the plug is inserted in the terminal base for inclusion in the circuit to be protected, the current flow between the terminal shell and the contact spring will be in two parallel or shunt paths through the fuse structure with which the contact spring engages, one path from the terminal shell to the contact spring being through 15 the lower part of the fuse band which has the main fusion point or section 39, and the other path being through the upper part of the fuse band which has the pilot fusion point or section 40. The resistance of the fusion point determines 20 the proportionate current flow therethrough, the resistance at the fusion point 40 being preferably such that there would be very little current flow therethrough but with the greater part of the current flow through the main fusion point 30 39. Upon excess current flow the fuse structure will blow simultaneously at both fusion points. There will be very little arcing or gassing at the pilot fusion point 40 and practically all of the 35 explosion, arcing and gassing will take place in the confined explosion chamber 16 through which the blown fuse extends.

The pilot fusion point 40 is visible, the top part B having a sight opening 47 in line with the top of the wall A over which these pilot fusion points 40 of the fuse structures extend. As a matter of protection and precaution, a transparent member such as a mica plate 48 is interposed between the cover part B and the wall 10, the mica pane shown being annular and surrounding the cylindrical lug 30 on the top member B, the mica pane being preferably perforated to receive projections or lugs 49 on top of the wall 10 so as to be held in proper position. After blowing of one of the fuse structures, the plug top B is rotated to swing the contact spring into engagement with an intact fuse structure and the sight opening 47 will then be in alignment with the pilot point 40 of such fuse structure. If this pilot fuse point or section is unbroken then it indicates that the 50 entire fuse structure is intact and ready for service.

It will be noted that the lower end of the wall 10 is tapered slightly on its outside so that the shell 36 may be readily applied. The shell was primarily of an internal diameter equal substantially to the outer diameter of the cylindrical part of the wall 10 above its tapered end so that when the shell is forced along the fuse bands extending along the outside of the wall 10 the shell will be slightly expanded and tensed so that it will exert clamping pressure against the fuse bands and make intimate contact therewith along an extended area, and, when the rim of the flange is deflected into the groove 46, the shell will be locked in place and the overlapping ends of the fuse bands will be clamped to the body A and held in electrical engagement. Should the terminal shell become heated while the plug is in service any resulting expansion thereof would 55 60 65 70 75

not be sufficient to loosen the shell and destroy its clamping action on the body A and against the fuse structures.

As shown on Figures 1 and 3 the flange part 12 5 may have on its top indications 50 which may be depressions as shown and which are located and spaced to accord with and indicate the proper position of the switch spring relative to the respective fuse structure.

10 Figure 8 shows a modified arrangement of fuse structure. It may be that it will be desirable to use fuse material in the form of wire instead of in the form of sheets or bands, particularly for the pilot fusion part of the fuse structure. In 15 the arrangement shown in Figure 8, channels or recesses 51 are provided in the inner side of the contact chamber 17 and each receives the coiled or folded end 52 of a length of wire fusing material, the outer end of the wire extending around 20 the top of the wall 10 and then downwardly for engagement with the terminal shell 36. The heavier fuse element 53 may also be of wire, or as shown, may be in the form of a fuse band with the fusion neck 54 within the explosion chamber 16. 25 The outer end of this fuse member will overlap the end of the wire fuse and be clamped in the groove 46 by the terminal shell. The inner end of the fuse band would extend upwardly through the passageway 42 into the contact chamber 17 30 and overlap the coiled end 52 of the wire fuse. This coiled end would have ample electrical engagement with the end of the fuse band and the ends of both fuse members would then be in electrical engagement with the contact spring as the 35 spring is brought into engagement with the fuse bands. In order to assure blowing of the wire fuse at a point where it crosses the top of the wall 10 and be visible through the mica pane and sight opening 47, the fuse at that point will be made of reduced cross-section as for example by being dented as indicated at 55.

40 The passageways 42 from the explosion chambers to the contact chamber are of such dimension that the fuse material extending therethrough will seal the passageways against the escape of flame or gas from the explosion chamber to the contact chamber when the fuse blows. The blowing at the pilot fusion point 40 will not 45 cause any material flame or gas so that the fuses can be carefully observed through the mica pane even at the instant when the fuse is blown.

50 I have shown practical and efficient embodiments of the features of my invention, but I do not desire to be limited to the exact construction, 55 arrangement and operation shown and described, as changes and modifications may be made without departing from the scope of the invention.

I claim as follows:

60 1. A fuse plug comprising a housing providing an explosion chamber and a terminal chamber separated by a partition, a passageway through said partition connecting said chambers, a terminal in said terminal chamber, a terminal on the outside of said housing, a fuse link extending from said outside terminal and through said explosion chamber and said partition passageway into said terminal chamber, said fuse link having a fusion part of low resistance located in said 65 explosion chamber, a light fuse link extending from said outside terminal and into said terminal chamber, the ends of said fuse links in said terminal chamber being adapted for engagement by said terminal in said chamber whereby said fuse 70 links will be connected in parallel between said 75

terminals, said light fuse link having a fusion part visible from the exterior of said plug.

2. In a fuse plug, the combination of a housing 5 providing a plurality of explosion chambers and a contact chamber, a partition between said explosion chambers and said contact chamber having passageways between said explosion chambers and said contact chamber, a stationary terminal for said plug on the outside of said housing, a movable terminal for said plug within said terminal chamber, fuse linkages between said terminals each comprising a comparatively heavy fuse link extending from said external terminal into one of said explosion chambers and through the corresponding passageway in said partition into 15 said contact chamber and a comparatively light fuse link extending from said external terminal into said contact chamber, means for moving said internal contact for selective engagement with the corresponding ends of said fuse linkages 20 whereby the heavy and light links of said linkages will be connected in parallel in the circuit with which the plug may be associated, said heavier fuse links having weakened fusion sections located within the respective explosion chambers, and 25 said lighter fuse links having weakened fusion sections visible from the exterior of the plug.

3. In a fuse plug, a housing comprising an annular wall having a cross partition providing a contact chamber above the partition, walls forming explosion chambers below said partition, said partition wall having passageways connecting said explosion chambers with said contact chamber, fuse linkages extending around said annular wall, each fuse linkage extending through said 30 contact chamber and through one of said partition passageways and one of said explosion chambers, an external plug terminal engaging with the outside of said fuse linkages, a contact movable in said contact chamber for selective engagement with the inner sides of said linkages whereby said linkages will be connected in parallel between said external terminal and said contact, each linkage having a fusion part of comparatively low resistance located in the respective 45 explosion chamber and having a fusion part of comparatively high resistance outside of the explosion chamber and the contact chamber and visible from the exterior of the plug.

4. In a fuse plug, the combination of a housing 50 comprising an annular wall having a cross partition forming an explosion chamber below the partition and a contact chamber above the partition, said partition having passageways connecting the explosion chamber with the contact chamber, a 55 contact terminal on the outer side of said housing, a movable contact terminal in said contact chamber, and a plurality of fuse linkages, each fuse linkage comprising a light fuse link extending from said outer terminal contact and around the 60 top of said annular wall into said contact chamber and a heavier fuse linkage extending from the outer contact terminal around the lower end of said annular wall and through said explosion chamber and one of said partition passageways 65 and into said contact chamber whereby each linkage structure when engaged by the movable terminal contact will have its links included in parallel between the outer terminal contact and said movable contact, each heavier link having a fusion 70 part located within said explosion chamber, and each lighter link having a fusion part where it extends around the top of said annular wall, and means cooperating with said movable contact for making visible the fusion part of the light links. 75

5. In a fuse plug, a housing comprising an annular wall having a cross partition dividing said housing into a contact chamber and an explosion chamber, said partition wall having a passageway 5 connecting said chambers, a fuse linkage extending around said annular wall and through said partition passageway and said chambers, an external plug terminal engaging with the outside of said fuse linkage, an inner plug terminal engaging said linkage in said contact chamber, said linkage having a fusion part of comparatively low resistance located in the explosion chamber and having a fusion part of comparatively high resistance between said inner plug terminal and 10 the outer plug terminal and visible from the exterior of the plug. 15
6. In a fuse plug, inner and outer plug terminals, a fuse link connected at its ends with the outer plug terminal and intermediate its ends with the inner plug terminal, said link having a fusion part of comparatively low resistance at one side of said inner terminal and a fusion part of comparatively high resistance at the other side of said inner terminal, means forming an inclosure 20 for said low resistance fusion part, and means making said high resistance fusion part visible from the exterior of the plug. 25
7. A fuse plug having circuit contact terminals, a single fuse strip contacting at its ends with one 30 of said terminals and at an intermediate point with said other terminal whereby to interpose two parallel fuse sections between said terminals, one of said sections having a comparatively low resistance fusion portion and the other section having a comparatively high resistance fusion portion, means confining said low resistance fusion portion within said plug, and means rendering said high resistance fusion portion visible from the exterior of the plug. 35
8. In a fuse plug, an annular body providing a contact chamber in its upper part, a plurality of fuse linkages each comprising a link of comparatively low fusion resistance extending from 40 the upper edge of said annular body and to the exterior thereof, an outer terminal for said plug surrounding said body and contacting the outer ends of the links of the fuse linkages, a cover rotatable on said body, an inner terminal for said plug and a contact arm engaging therewith and rotatable with said cover for selective engagement with said fuse linkages, said cover having a sight opening in register with the upper edge of said body whereby said pilot fuse links may be visible from the exterior of the plug. 45
9. In a fuse plug, the combination of a body having partition walls providing a contact chamber in the upper part thereof and a plurality of explosion chambers in the lower part thereof, fuse linkages each comprising a main fuse section extending from the contact chamber through one of said explosion chambers and around the lower edge of said body to the exterior thereof and a pilot fuse section extending from the contact chamber around the upper edge of said body to the exterior thereof, a bottom member engaging the lower end of said body to close said explosion chambers, a cover part rotatably mounted on said body, an outer terminal for the plug surrounding said bottom part and the lower end of the body 20 part and contacting with the outer ends of the fuse sections of said fuse linkages, an inner terminal for said plug extending through said body and said bottom part and cover part and serving to hold said parts axially together, and a contact arm in said contact chamber connected with said inner terminal and movable with said cover part for selective engagement with said fuse linkages, said cover part having a sight opening through which the pilot fuse links of said fuse linkages 25 are visible from the exterior of the plug. 30

HENRY RUSKIN.
